LIQUID SPRAYER CONSTRUCTION

Filed April 29, 1930

Inventor
Robert M. Bagley.
By Leonard L. Kalish
Attorney.

UNITED STATES PATENT OFFICE

ROBERT M. BAGLEY, OF HADDONFIELD, NEW JERSEY, ASSIGNOR TO THE R. M. HOLLINGSHEAD CO., OF CAMDEN, NEW JERSEY, A CORPORATION OF NEW JERSEY

LIQUID SPRAYER CONSTRUCTION

Application filed April 29, 1930. Serial No. 448,214.

My invention relates to a new and useful liquid sprayer construction, including an air pump, a liquid container, and means for drawing the liquid from the liquid container and atomizing the same by a jet of air, where- 5 in a drip-collecting baffle may be provided at the discharge end of the pump in a quick and easy manner, and whereby said drip-collecting baffle may be made durable and 10 at the same time inexpensive.

With the above ends in view, my invention consists of a manually operable air pump having an elongated, cylindrical body within which a piston is adapted to be re- 15 ciprocated by a piston rod having an external handle. According to my invention I form the discharge end of the pump by a series of telescoping members, one forming the end wall of the cylinder of the air pump, and the 20 other forming the drip-collecting baffle plate. According to my invention, the end wall of the cylinder of the air pump is provided with a comparatively deep, cylindrical flange which is adapted to telescope within the end 25 of the cylinder of the air pump, while the drip-collecting baffle is provided with a cylindrical flange of lesser depth, which is adapted to telescope within the cylindrical flange of the end plate. The end of the cylinder of the 30 air pump, as well as the cylindrical flange portions of the end plate and baffle plate, are all provided with annular seaming rims, which, when the three members are assem- 35 bled, are adapted to be rolled over each other to form a single, integral seam between the three separate members, whereby a single unitary construction is obtained of great durability and low cost.

For the purpose of illustrating my invention, I have shown in the accompanying drawing one form thereof which is at present preferred by me, since the same has been found in practice to give satisfactory and reliable results, although it is to be under- 45 stood that the various instrumentalities of which my invention consists can be variously arranged and organized and that my invention is not limited to the precise arrangement and organization of the instrumentalities as 50 herein shown and described.

Referring to the drawing, in which like reference characters indicate like parts,

Figure 1 represents a longitudinal section of a liquid sprayer embodying my invention,

Figure 2 represents a front elevation of the same on an enlarged scale.

Figure 3 represents a fragmentary sectional view of the discharge end of the sprayer, on an enlarged scale.

Figure 4 represents a fragmentary sectional view of the front end of the pump dismantled.

Figure 5 represents a fragmentary sectional view similar to that shown in Figure 3, 65 illustrating a modified form of construction.

In carrying out my invention I provide a pump cylinder 6, formed of sheet metal and seamed by a longitudinal seam (not shown in the drawing). A terminal block 7, of wood or the like, is inserted into the rear end of the cylinder 6, to form a closure therefor and to support and guide the piston rod 8. The terminal block 7 is retained in the end of the cylinder 6 by a series of screws 9, or 70 any other suitable means. The piston rod 8 passes through an axial opening in the terminal block 7, and carries at its outer end a suitable handle 10. To the inner end of the piston rod 8, a cup shaped leather washer 11 is secured, which together with the supporting metal washer 12 forms a piston effective in compressing air in advance of the washer 11. The free or loose washer 13 carried on the outer end of the piston rod 8, 75 and the lugs 14 pressed from the sides of the rod 8, serve to limit the stroke of the piston, by abutting against the outer wall of the terminal block 7.

The discharge end of the cylindrical body 6 is flanged outwardly to a slight extent, as indicated at 15 in Figure 4. The terminal wall member of the cylinder, designated generally by the numeral 16 (Fig. 4) is formed cup-shaped, including the transverse wall 17, 80 with its central discharge opening or port 18, and the cylindrical wall portion 19 of suitable length, adapted to telescope within the end of the cylinder 6. A seaming flange 20 is also formed on the outside or pre-edge. 100

of the cylindrical wall portion 19, which is ultimately adapted to overlap the seaming flange 15 on the cylinder 6.

A baffle member, designated generally by the numeral 21 (Fig. 4) is provided with a generally conical portion 22, having a horizontally disposed elliptical opening 23 therein. The baffle member 21 is also provided with a slight cylindrical portion 24, which is adapted to fit within or telescope within the cylindrical portion 19 of the terminal member 16, to a slight extent. The slight cylindrical portion 24 of the baffle member 21 then is flared outwardly into a seaming flange 25, which is adapted to be rolled over the seaming flanges 20 and 15 of the terminal member 16 and cylinder 6 respectively. By so uniting the assembled parts, as shown particularly in Figure 3, by a single rolled or crimped seam 26, a firm and durable construction is obtained, with a minimum of cost and operation.

Corresponding openings 27 and 28 are provided in the cylinder wall 6 and in the cylindrical wall 19 of the terminal member 16, so when the two are assembled in the manner shown particularly in Figure 3, the two holes will coincide and provide a perforation through the double thickness of metal, for the reception of the liquid suction tube 29 of the sprayer. The holes 27 and 28 are slightly larger than the liquid suction tube 29, so as to provide some clearance around the outside of the tube 29, for draining back the drippings into the liquid container 30.

The liquid container 30 (Fig. 3) is provided with a perforation 31, preferably somewhat larger than the perforations 27 and 28, for the reception of the liquid suction tube 29. The aperture 31 is made somewhat larger so that the apertures 27 and 28 may be more readily matched with the aperture 31 during the assembling operation, without the exercise of too much care or without consuming too much time.

In assembling my novel liquid sprayer construction, I first assemble the terminal member 16 and the baffle member 21 upon the end of the cylinder 6, by means of the seam 26. During the assembling of these parts, care must be merely taken to match the aperture 28 with the aperture 27 in the cylinder 6. The apertures require no further attention during the entire assembling, because the member 16 will telescope into the cylinder 6 with sufficient friction to retain the former within the latter securely during the seaming operation.

Thereafter, the liquid suction tube 29 is inserted through the apertures 27 and 28, and secured against the transverse wall 17 by means of solder, as at 32, with the top of the tube disposed at the center of the aperture 18, so that the jet of air emerging from

the aperture 18 will draw the liquid through the tube 29, in the usual manner.

The pump cylinder 6 is then superimposed upon the container 30, in a manner shown in Figures 2 and 3, with the tube 29 extending through the aperture 31 in the container. The cylinder 6 is then affixed to the container 30 by soldering, as at 33.

The container 30 may be provided with any suitable opening 34, through which the liquid may be inserted into the container.

The pump 6 is also provided with an inlet port 35, through which the air may be taken into the cylinder.

The liquid sprayer thus assembled and completed produces a very firm and durable construction, and one which may be produced at a minimum cost.

Due to the horizontally disposed elliptical opening 23 in the baffle wall 22, a generally horizontal, fan-shaped spray is emitted from the sprayer, thereby tending to give the maximum distribution of spray for a given amount of liquid.

Any liquid which coagulates into distinct drops before the stream of air has an opportunity fully to disperse the same, drips on to the baffle plate 22 and flows down into the chamber 36, formed between said baffle plate and the terminal wall 17, from whence it drains back into the container 30 through the apertures 27 and 28 and the aperture 31. Thus, the liquid is conserved to the maximum extent.

In Figure 5 I have shown a modified construction embodying my invention, wherein the cylinder 6 instead of being affixed to the body of the liquid container 30, is merely affixed to a screw cap or other similar closure member 37, to which in turn, a liquid container 38 may be detachably secured in the manner shown in the drawing. By this means the same pump may be attached to any one of several containers, and the liquid may be used directly from the container in which it is shipped and sold. Thus, it is merely necessary to unscrew the usual screw cap of the container and replace it with the screw cap portion 37 of the pump 6.

I am aware that my invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and hereby desire to secure by Letters Patent, is:—

1. A liquid sprayer including a pump cylinder having a terminal wall and a baffle plate secured to the end thereof, in spaced relation to each other, by a single crimped seam; said

baffle plate having a horizontally disposed elliptical opening, and spraying means operatively disposed between said terminal wall and said baffle plate and in operative relation to said elliptical opening.

5 2. A liquid sprayer including a pump cylinder having a lateral aperture near the discharge end thereof, a terminal wall member telescoped into the end of said pump cylinder and having a centrally perforated transverse 10 terminal wall portion and a perforated cylindrical portion, the perforation in said cylindrical portion being generally in registration with said lateral aperture in said pump cylinder, a baffle member telescoped into said terminal wall member; spraying means operatively disposed between said terminal wall and said baffle member, said pump cylinder, terminal wall member and baffle member being united to each other permanently by a 15 single crimped seam.

3. A liquid sprayer including a pump cylinder having a lateral aperture near the discharge end thereof, a terminal wall member including a centrally perforated transverse wall portion and a perforated cylindrical wall portion, telescoped into the end of said pump cylinder, with the cylindrical wall perforation of said terminal wall member corresponding with the perforation in said pump cylinder, and a baffle member having a slight cylindrical portion telescoped into said cylindrical portion of the terminal wall member, and having a conical baffle portion with a horizontally disposed elliptical opening, said cylinder, terminal wall member, and baffle member, being permanently united by a single, crimped seam, and spraying means operatively disposed between said terminal wall member and said baffle member and in operative relation to said elliptical opening.

4. A liquid sprayer including a pump cylinder having a lateral aperture near the discharge end thereof, a terminal wall member including a centrally perforated transverse wall portion and a perforated cylindrical wall portion, telescoped into the end of said pump cylinder, with the cylindrical wall perforation of said terminal wall member corresponding with the perforation in said pump cylinder, and a baffle member having a slight cylindrical portion telescoped into said cylindrical portion of the terminal wall member, and having a conical baffle portion with a horizontally disposed elliptical opening, said cylinder, terminal wall member, and baffle member, being permanently united by a single, crimped seam, and a liquid container attached to said pump cylinder, and a liquid suction tube extending from said liquid container through said perforations in the cylinder and cylindrical portion of the terminal wall member into operative juxtaposition to the central perforation in the terminal wall; said liquid suction member being of a cross-sectional area

less than the perforations through which it passes, so as to permit the return of liquid drippings through said perforations, said liquid suction tube being in operative juxtaposition to said elliptical opening.

5. A liquid sprayer including a pump cylinder having a lateral aperture near the discharge end thereof, a terminal wall member including a centrally perforated transverse wall portion and a perforated cylindrical wall portion, telescoped into the end of said pump cylinder, with the cylindrical wall perforation of said terminal wall member corresponding with the perforation in said pump cylinder, and a baffle member having a slight cylindrical portion telescoped into said cylindrical portion of the terminal wall member, and having a conical baffle portion with a horizontally disposed elliptical opening, said cylinder, terminal wall member, and baffle member, being permanently united by a single, crimped seam, and a liquid container closure member attached to said pump cylinder, and a liquid suction tube extending through said liquid container closure member through said perforations in the cylinder and cylindrical portion of the terminal wall member, into operative juxtaposition to the central perforation in the terminal wall; said liquid suction member being of a cross-sectional area less than the perforations through which it passes, so as to permit the return of liquid drippings through said perforations, said liquid suction tube being in operative juxtaposition to said elliptical opening.

In testimony whereof I have hereunto set my hand this 25th day of March, 1930.

ROBERT M. BAGLEY.
